UNITED STATES PATENT OFFICE.

JOSEPH P. MAGNEY AND WILLIAM H. MASTERMAN, OF LOS ANGELES, CALIFORNIA, FREDERICK R. KELLOGG, ADMINISTRATOR OF SAID MASTERMAN, DECEASED, ASSIGNORS TO NATIONAL ENGINE COMPANY, OF LOS ANGELES, CALIFORNIA, A CORPORATION OF ARIZONA TERRITORY.

COMPOUND FLUID-PRESSURE MOTOR.

No. 823,060.

Specification of Letters Patent.

Patented June 12, 1906.

Application filed August 1, 1905. Serial No. 272,162.

To all whom it may concern:

Be it known that we, JOSEPH P. MAGNEY and WILLIAM H. MASTERMAN, citizens of the United States, residing at Los Angeles, in the county of Los Angeles and State of California, have invented a new and useful Compound Fluid-Pressure Motor, of which the following is a specification.

An important object of the invention is to reduce the back pressure which exists in the high-pressure cylinder or cylinders of compound engines or fluid-pressure motors. In such engines each of the lower-pressure cylinders is usually supplied with operating fluid from the low-pressure side of the cylinder at next higher pressure, so that there is necessarily a back pressure on such low-pressure side equal to the intake pressure on the next cylinder.

20 This invention provides for materially reducing the amount of this back pressure by supplying the low-pressure cylinder from the high-pressure cylinder at intermediate pressure, the fluid for operating the low-pressure cylinder being taken from the high-pressure cylinder before it has been fully expanded therein.

25 A further object of this invention is to provide a fluid-pressure motor of the rotary type wherein the expansive force of the steam or operating medium is utilized in a series or plurality of operations at successively lower pressure, thereby obtaining the advantages of economy due to compounding.

30 35 A further object of the invention is to diminish and utilize the leakage which occurs in rotary engines.

The accompanying drawings illustrate the invention.

40 Figure 1 is a plan. Fig. 2 is a longitudinal vertical section on line $x^1 x^3$, Fig. 1. Fig. 3 is a transverse section on line $x^2 x^3$, Fig. 1. Fig. 4 is a transverse section on line $x^4 x^5$, Fig. 1. Fig. 5 is a transverse section on line $x^5 x^6$, Fig. 1. Fig. 6 is a section on line $x^6 x^8$ in Fig. 4.

45 The engine is herein shown as a triple-expansion engine; but it will be understood that any number of expansions may be used.

1, 2, and 3 designate, respectively, the high-pressure, intermediate-pressure, and low-pressure cylinders or casings, which are

arranged longitudinally in line with one another and provided with flanges 4, whereby they are bolted to end and intermediate plates 5 6 7 8. Two shafts 9 9' are journaled in the ends or plates 5 6 7 8 by bearings 25 26 and extend parallel to one another longitudinally within the cylinders. Rotors or piston members are arranged in pairs, as at 10 10' 11 11' 12 12', in the respective cylinders, the said piston members being toothed or formed as gears, as at 13, to engage or intermesh with one another to prevent the passage of steam therebetween. A part of the inner face or wall of each cylinder-chamber 65 is reentrant or shaped, as at 14, to fit or conform to the peripheral pistons of the teeth of the pair of pistons therein, so that the pistons will make a substantially steam-tight joint in passing over said wall portion, and it is at 70 this reentrant portion of the piston movement that the fluid-pressure is exerted thereon. The pistons 10 11 12 are fixed on their shaft 9, and one of the pistons—say 10'—on the other shaft may also be fastened; but 75 the other pistons—say 11' 12'—are preferably loose on shaft 9' to insure steam-tight engagement of the teeth.

15 designates a high-pressure steam-inlet pipe communicating through port 15' into 80 the high-pressure cylinder-chamber at the reentrant portion aforesaid at the point where the paths of the piston peripheries diverge. 16' 17' designate similar inlet-ports in the intermediate or low pressure cylinders. Means are provided for supplying to the inlet-port 16' of the intermediate-cylinder steam or fluid-pressure medium from a point in the high-pressure cylinder, which is at a pressure below the maximum pressure 90 therein. Said means may consist of a branched or V pipe 16, connected to said inlet-port 16' and communicating with ports 16'', arranged in the wall portion 14 at points on either side of the central inlet-port 95 15, and sufficiently remote therefrom to insure that a tooth or peripheral portion 13 of each piston will always extend between the high-pressure inlet-port and this intermediate pressure outlet-port on each side. Located in said portion 14 at a point still more remote from the central inlet 15' and at each

side thereof is another outlet-port 17", communicating through the respective branches of the V-pipe 17 with the inlet-port 17' of the low-pressure cylinder. Said branches of the V-pipe 17 also have communication through ports 17^a, opening into the wall portion 14 of the intermediate pressure-cylinder 2 at each side of the central inlet portion 16' at positions corresponding to the position of the ports 16" in the high-pressure cylinder. Beyond the port 14 the inner wall of each cylinder may be recessed or made larger, as shown at 18, so as to be clear of the teeth or peripheral portions of the pistons, thereby diminishing the friction and forming a space or chamber 19 for the free passage of steam at the low-pressure side of the pistons. This chamber may communicate by opening 19' or 19^a with the low-pressure conduits or ports 17". In the low-pressure cylinder the corresponding space or chamber 20 has an outlet or exhaust-port connection 20'. 21 designates ribs which extend across the ports 15' 16' 17' to strengthen the structure.

25 Means are provided for oiling the engine through the shafts thereof, said means consisting of oil-supply pipe 22, communicating through branch pipe 23 with couplings 24 on bearings 25 at one end of the respective shafts 9 9', said shafts having longitudinal bores 27 and outlets or perforations 28 extending therefrom to the bearings 25, 26, 29 of the shaft in the walls 5 6 7 8. Said shafts are closed at the other end and provided with stuffing-boxes 30 31'. 31 designates the pulley on the shaft 9 for taking off the power therefrom.

The operation is as follows: Steam or fluid pressure medium being admitted at inlet 15 of the high-pressure cylinder fills the space between the teeth of the piston members or rotors immediately adjacent thereto. The teeth of the said members mesh with one another in such a manner as to make a substantially steam-tight joint at their point of contact or engagement, and the areas exposed to pressure on the teeth are unbalanced or unequal in opposite circumferential directions, so that there is a resultant circumferential pressure on the rotors acting to turn same in the direction of the arrows in Fig. 3. As each intertooth space which has thus been exposed to receive fluid steam-pressure from the inlet passes under the portion 14 of the cylinder-wall it will carry with it the steam pocketed therein, and as said space comes into communication with the port 16" said steam will escape through said port to a greater or less extent, dependent upon the size of said port and the velocity of the piston member. For example, the pressure in the pipe 16 or at the intake side of the intermediate cylinder may be maintained at about one-half that of the pressure at the inlet 15, and in that case the ports 16" will be

proportioned to deliver to withdraw from the intertooth space aforesaid about one-half of the steam therein contained, the pressure in said space being simultaneously reduced to about one-half the original pressure. In the further rotation of the piston members said intertooth space is closed by a further wall portion 14 of the cylinder-casing and is then brought into communication with the port 17", leading to the low-pressure cylinder, which port will draw steam from said space, reducing the pressure therein to, say, one-fourth of the original pressure. Then in the further rotation said intertooth space will be brought into communication with the low-pressure chamber 19 of the high-pressure cylinder, which chamber is in permanent connection with the high-pressure side of the low-pressure cylinder. While this operation is taking place in the high-pressure cylinder the steam which passes at intermediate pressure—say fifty-one pounds—from the ports 16" to the inlet 16 of the intermediate cylinder enters the latter between the tooth of the piston members thereof, which are immediately adjacent to the inlet and operates thereon to produce rotation of said piston members, and in such rotative movement the steam is pocketed between the intertooth spaces and carried around to the ports 17^a at which it is withdrawn at low pressure to the intake of the low-pressure cylinder. Thus the pistons open communication necessarily with the inlet and outlet ports 15' 16" 17", the steam first exerting its force at full pressure in the high-pressure cylinder and being then divided apart, say, one-half, being used at half pressure in the intermediate-pressure engine and the other part passing around in the high-pressure cylinder, and being taken to the low-pressure cylinder together with the first portion coming from the intermediate cylinder.

It will be noted that the back pressure in the high-pressure cylinder is lower than the pressure at the intake of the intermediate cylinder, being, for example, twenty-five pounds, with one hundred pounds high pressure and fifty pounds intermediate pressure, whereas with the ordinary system of compounding the back pressure in the high-pressure cylinder would be the same as the pressure at the intake of the intermediate cylinder, say, fifty pounds. An increase of power and work developed is thereby obtained from the high-pressure cylinder. Advantage is also obtained by the restriction of the high-pressure zone in the cylinder to a point immediately adjacent to the inlet. By reducing the extension of the area or movement over which the high pressure is exerted the amount of leakage and also the side thrust on the shafts are greatly reduced.

What I claim is—
1. A compound engine comprising a high-

pressure cylinder having a high-pressure inlet and intermediate pressure and low-pressure outlets and a cylinder having an inlet connection to the intermediate pressure-outlet of the high-pressure cylinder.

2. A compound engine comprising a high-pressure cylinder having an inlet-port and having a plurality of outlet-ports and a piston member movable in the cylinder and provided with fluid-receiving means communicating, in the movement of said piston member, successively with the inlet-port and with the outlet-ports for delivering to said outlet-ports fluid at successively lower pressures and cylinders having supply connections respectively to said outlet-ports.

3. A compound engine comprising a high-pressure cylinder and a lower-pressure cylinder connected to the high-pressure cylinder at a point of intermediate pressure therein.

4. A compound engine comprising a plurality of cylinders, rotary piston members therein having intermeshing teeth, the wall of each cylinder having a portion extending between the piston members to fit the peripheral faces of the teeth, and provided with a central inlet-port, said wall portion of one of the cylinders being provided with an outlet-port at one side of the inlet and a connection between said outlet and the inlet of another cylinder.

5. A compound engine comprising a plurality of cylinders, rotary piston members therein having intermeshing teeth, the wall of each cylinder having a portion extending between the piston members to fit the peripheral faces of the teeth, and provided with a central inlet-port, said wall portion of one of the cylinders being provided with an outlet-port at each side of the inlet and a connection between said outlet and the inlet of another cylinder.

6. A compound engine comprising a high-pressure cylinder having a high-pressure inlet and intermediate and low pressure outlets, piston members in said cylinder movable to open communication with said ports successively, an intermediate-pressure cylinder having an inlet connected to the aforesaid intermediate outlet-port of the high-pressure cylinder and having an outlet connected to the aforesaid low-pressure outlet-port of the high-pressure cylinder.

7. A compound engine comprising a high-pressure cylinder having a high-pressure inlet and intermediate and low-pressure outlets, piston members in said cylinder movable to open communication with said ports successively, an intermediate-pressure cylinder having an inlet connected to the aforesaid intermediate outlet-port of the high-pressure cylinder and having an outlet connected to the aforesaid low-pressure outlet-port of the high-pressure cylinder, and a low-pressure cylinder provided with an outlet

and having an inlet-port connected to the low-pressure outlet of the high-pressure cylinder and to the outlet of the intermediate-pressure cylinder.

8. An engine comprising two rotary piston members provided with intermeshing teeth and a cylinder inclosing said members and having a wall portion extending between the members and fitting the peripheral faces of the teeth of said members, said wall portion formed with inlet and outlet ports, and the inner wall of the cylinder being clear of the piston members at other points.

9. An engine comprising two rotary piston members formed as intermeshing gears and a cylinder inclosing said gears and formed on one wall with a face portion extending between said gears and fitting the peripheral faces of the teeth thereof, said face portion being provided with inlet and outlet ports and the remaining portion of said wall of the cylinder being separated from the gears to form a low-pressure chamber in the cylinder, the cylinder being provided with an exhaust-port communicating with said low-pressure chamber.

10. An expansive fluid-pressure engine comprising a cylinder, piston means movable therein and dividing the cylinder into high-pressure, intermediate-pressure and low-pressure portions, said cylinder being provided with ports communicating respectively with said high-pressure, intermediate-pressure and low-pressure portions, a supply connection to the high-pressure port and an engine-cylinder having a supply connection from the intermediate-pressure port.

11. An expansive fluid-pressure engine comprising a cylinder having high-pressure and low-pressure ports, and provided with an outlet connection from a point of intermediate pressure.

12. An expansive fluid-pressure engine comprising a cylinder having high-pressure and low-pressure ports, and provided with an outlet connection from a point of intermediate pressure, and means for conducting away and utilizing the fluid from said intermediate-pressure outlet.

13. An expansive fluid-pressure engine comprising a cylinder having high-pressure and low-pressure ports, and provided with an outlet connection from a point of intermediate pressure, and piston means connected to and utilizing the fluid from said intermediate-pressure outlet.

In testimony whereof we have hereunto set our hands, at Los Angeles, California, this 24th day of July, 1905.

JOSEPH P. MAGNEY.
